ELECTRIC SWITCH

Original application filed May 16, 1929, Serial No. 360,781. Divided and this application filed August 4, 1930. Serial No. 473,000.

This invention relates to electric switches, and more particularly to improved locking means for maintaining a switch in closed position.

The locking device herein shown and described may be applied to any type of switch which requires positive locking means, but it is especially adapted for use on high tension switching equipment wherein the switch is ordinarily manipulated by means of a switch stick or fuse puller, the operator locating himself at a safe distance from the live equipment.

In the design and construction of a practical locking mechanism for manually operable high tension switches, it is desirable that the releasing member may be readily engageable by the switch stick without complicated manipulations of that member. Obviously, the locking means must be positive in operation to prevent opening of the switch under severe or unusual electrical or weather conditions.

It is an object of this invention to provide an improved switch locking mechanism of simple construction, adapted to operate automatically upon closing of the switch, and which may be readily and positively operable at a distance therefrom.

A further object of this invention lies in the provision of a switch lock in which the latch and manipulating members are separate, and individually operable, whereby pressure on the latter member to close the switch, does not interfere with the movement of the former to prevent its sliding over a stationary catch and coming into subsequent locking engagement therewith.

These and other objects and advantages will appear from the following description and from the drawing, in which Fig. 1 is a fragmentary side elevation showing a stationary, insulated contact structure of a type employed on high tension switches, and the free end of a fuse cartridge operatively associated therewith and locked thereto by means contemplated by this invention; Fig. 2 is a side elevation of the device of this invention shown mounted on the end of a fuse cartridge of expulsion type; Fig. 3 is a sec-

tional view taken along the line 3—3 of Fig. 2; Fig. 4 is a perspective view of the lock manipulating or releasing member, and Fig. 5 is a perspective view of the latch member.

The contact structure shown in Fig. 1 forms no part of the present invention, it being illustrative of a single application of my device, but is fully described in my co-pending application, Serial No. 360,781, filed May 6th, 1929, of which the present application is a division. Briefly, however, the contact assembly comprises paired contact shoes 6, which are mounted on conducting arms 7, supported by a bracket 8, carried by an insulator 9. A connector or lug 10 provides means for connecting the structure to a line, which may be connected to the lug by solder or set screws, (not shown). In the present embodiment the contact shoes 6 are provided with lateral projections 11 which serve as catches or keepers for the latch member to be hereinafter described. While the contact shoes in the present instance are capable of self-aligning movement to insure good contact with the blade member, this movement is in no wise necessary to the operation of the locking mechanism, and the catches may be considered stationary for the purposes of this application.

The switch blade is provided with a pair of spaced arms 12 through which is disposed a bearing pin 13 adapted to pivotally support the latch member 14 and the manipulating member 15. The latch member 14 comprises a channel shaped body portion 16 having paired latching arms 17 extending from opposite sides thereof and of such conformation as to be enabled to straddle the switch blade as shown in Fig. 3. The arms 17 terminate in hooked portions 18, which are normally disposed in position to engage the catches 11, being urged into engaging position by a spring 19. The hooked portions 18 are provided with arcuate surfaces 20 which contact with the stationary catches 11, shown in Fig. 1, when the switch is being closed, causing the latch member to be rotated slightly, relative to the switch blade, against the action of the spring 19. When the switch is fully closed, the hook portions, now clear of

the catches, are urged into locking position.

The manipulating member 15 comprises, preferably, a ring 21, having an arm 22 extending tangentially therefrom. The arm 22 pivotally engages the pin 13 between the walls of the latch body 16. Movement of the member 15 to release the latch, causes the portion of the arm 22, indicated at 23, to bear against the latch body 16 and rotate that member into releasing position. The limit of relative movement of the latch mechanism is reached when the corner portions, indicated at 24, of the latch member 14, abut against the surface of the switch blade, and the application of further force causes the switch to be opened.

It will be obvious that the simple form of manipulating member herein shown and described is advantageous in that no specially formed tool requiring complementary engaging portions is necessary, but any device employing an insulating handle and having a portion adapted to enter the ring 21 may be conveniently employed to open or close the switch.

While I have shown and described my invention as applicable to a fuse cartridge of the expulsion type, it will be obvious that the same may be applied to any switch blade, as it is well understood in the art and common practice to substitute switch blades for fuse cartridges, and vice versa.

While I have shown and described a particular embodiment of my invention, it will be obvious to those skilled in the art that certain changes may be made without departing from the spirit and full intended scope of the invention as defined in the appended claims.

I claim as my invention:

40. 1. In a switch assembly a switch blade and contacts adapted for current conducting and locking engagement, respectively, by said blade and by a latch mechanism associated with said blade, said latching mechanism including a channeled body carried by said blade, integral latching arms projecting angularly from opposite sides of said body, laterally overhanging said blade and contacts, keepers for said arms, formed by lateral projections on said contacts, means on the latch arms forming cam surfaces for directing said arms into latching position, a latch releasing element comprising a ring having a tangential arm portion projecting into said channeled body, a pivot common to said body member and releasing element and a resilient member acting on said body and tending to urge said arms into latching position.
60. 2. In a switch assembly including a switch blade and a relatively stationary switch-contact assembly having laterally spaced, self-aligning contact shoes, keepers formed by lateral extensions on said contacts, a latching mechanism carried by said blade,

and including a channel shaped member, integrally formed latch arms extending angularly from opposite sides, at one end of said member and overlying the blade and fixed contacts so as to engage said keepers when the switch blade is in closed position, a spring in bearing engagement with the central portion of said channel member at the end thereof opposite said latch arms, said spring tending to urge said latch arms into latching position, a latch releasing member comprising a ring having a tangential arm portion extending endwardly into said channel member, and a pivot element common to said channel and arm portion, and carried at one side of the switch blade, said channel member and latch releasing member being adapted for individual swinging movement about said pivot element.

3. In a switch assembly, a switch blade, a contact portion near one end of the switch blade provided with opposite, lateral contact surfaces, a pair of spaced, parallel fixed contacts adapted to engage the contact surfaces on the blade, a blade-latching device including a pair of pivot arms disposed between the planes of said blade contact surfaces, and at one side of the blade contact portion, a pivot journaled in said arms, a one-piece, bifurcate latch carried by said pivot and having its legs extended into overlying, spaced relation to said blade contact surfaces, terminal locking lugs on said legs, a latch-actuating lever extending between the legs of the latch and mounted for a limited rotation on the latch pivot, a latch spring carried at one side of the contact portion of the blade, and bearing against the central portion of the latch, and a keeper formed by a lateral projection on each of the fixed contacts, the projections adapted for releasable latching engagement by said locking lugs.
